UNITED STATES PATENT OFFICE

WINTHROP L. JACOBS, OF JERSEY CITY, NEW JERSEY, ASSIGNOR TO
HARTFORD CARPET COMPANY, OF HARTFORD, CONN.

DESIGN FOR CARPET.

Specification forming part of Design No. **11,373**, dated August 26, 1879; application filed August 2, 1879.
[Term of patent 3½ years.]

To all whom it may concern.

Be it known that I, WINTHROP L. JACOBS, of Jersey City, in the county of Hudson and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

Upon the background are scattered a large number of irregular figures, arranged as represented in the photograph, to produce the design. The more prominent of these figures are the following:

a is a cross-shaped figure, having upwardly inclined arms and a central rosette. *b* is a bar having two parallel zigzag projections and a central richly-ornamented top piece. The figure *d* is composed of two rectangular segments placed opposite to each other, with smaller ornaments between them.

e is a hexagon surmounted by an ornamental top. It has two zigzag side projections and semicircular corner-pieces. A rectangular figure, *f*, is surrounded by a multitude of triangular circular rosette-shaped and smaller irregular figures. *g* is a rectangular segment,

with scalloped outline and two small square projections.

The hexagon *h* has sidewardly-projecting rosettes, a triangular top piece, and parallel zigzag bars.

The figure *i* is composed of two rows of rosettes, two crown-shaped ornaments, a semi-oval top piece, and smaller ornamentations.

j is another irregular figure, composed of two small squares, a central oval, and zigzag side pieces.

I claim—

1. The design for a carpet, consisting of the figures *a b*, substantially as shown.
2. The design for a carpet, consisting of the figures *d e*, substantially as shown.
3. The design for a carpet, consisting of the figures *g h*, substantially as shown.
4. The design for a carpet, consisting of the figures *i j*, substantially as shown.
5. The design for a carpet, consisting of the figures *a b d e*, substantially as shown.
6. The design for a carpet, consisting of the figures *g h i j*, substantially as shown.
7. The design for a carpet, consisting of the figures *a b d e f g h i j*, substantially as shown.
